RATCHET WRENCH

Hugh T. Greenlee, Gates Mills, Ohio, assignor to The Wright Tool and Forge Co., Barberton, Ohio, a corporation of Ohio

Filed June 7, 1962, Ser. No. 70,464

Term of patent 14 years

(Cl. D54—16)

FIG. 1 is a top plan view of a ratchet wrench showing my new design;

FIG. 2 is a bottom plan view thereof;

FIG. 3 is an end elevational view taken from the left of FIG. 1;

FIG. 4 is an end elevational view taken from the right of FIG. 1;

FIG. 5 is a top perspective view thereof; and

FIG. 6 is a bottom perspective view thereof.

This application is a continuation-in-part of my co-pending applications Serial No. D-57,858, filed October 8, 1959, and Serial No. D-59,182, filed January 27, 1960, both now abandoned.

I claim:

The ornamental design for a ratchet wrench, as shown.
